UNITED STATES PATENT OFFICE.

PAUL CHARLES MORRIS, OF YOUNGSTOWN, OHIO.

DESIGN FOR AN INCENSE BURNER.

Application filed November 24, 1924. Serial No. 11,457. Term of patent 3½ years.

To all whom it may concern:

Be it known that I, PAUL CHARLES MORRIS, a citizen of the United States, residing at Youngstown, in the county of Mahoning and State of Ohio, have invented a new, original, and ornamental Design for Incense Burner, of which the following is a specification, reference being had to the accompanying drawing, forming part thereof.

Figure 1 is a perspective view of the incense burner, showing my new design.

I claim:

The ornamental design for an incense burner, as shown.

PAUL CHARLES MORRIS.
